(57) **CLAIM**

The ornamental design for a hip brace with handle for dog, as shown and described.

DESCRIPTION

FIG. 1 is a front perspective view of a hip brace with handle for dog, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines on the hip brace with handle for dog depict stitching that forms no part of the claim. The broken lines showing a dog depict environmental structure that forms no part of the claimed design. All broken lines form no part of the claim. The drawings are shaded to indicate contrasting surfaces.
